UNITED STATES PATENT OFFICE.

MAX APSTEIN, OF SOUTH NORWALK, CONNECTICUT.

RAZOR-BLADE HOLDER.

1,201,231.

Specification of Letters Patent. Patented Oct. 17, 1916.

Application filed December 31, 1915. Serial No. 69,660.

To all whom it may concern:

Be it known that I, MAX APSTEIN, a citizen of the United States, residing at South Norwalk, in the county of Fairfield and State of Connecticut, have invented certain new and useful Improvements in Razor-Blade Holders; and I do hereby declare the following to be a full, clear, and exact description of the invention, such as will enable others skilled in the art to which it appertains to make and use the same.

This invention relates to new and useful improvements in a razor blade holder, and one of its objects is the provision of a device of this character, which shall be simple, durable and efficient, and which may be manufactured and sold at a comparatively low cost.

A further object of this invention is the provision of a pair of handles hinged together at one of their ends and provided with a strop engaging portion to support a razor blade in an inclined or sharpening position on a strop.

A still further object of this invention is the provision of a pair of pegs secured to one of the handles and received in alining sockets of the other handle, when the handles are in closed position to receive and clamp a razor blade therebetween, and one of the pegs is inclined in the direction of the other peg to securely hold said razor blade upon the pegs at all times.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which:

Figure 1 is a side elevation of a razor blade holder constructed in accordance with my invention, illustrating an ordinary Gillette razor blade clamped in position, Fig. 2 is a longitudinal sectional view, taken on the line 2-2 of Fig. 1, illustrated in dotted lines one of the handles raised to a vertical position, Fig. 3 is a side elevation illustrating the handles in an open position, and Fig. 4 is a detail sectional view taken on the line 4-4 of Fig. 1.

Referring in detail to the drawings, 1 and 2 indicate handles secured together by a hinge 3 and the handle 1 is provided with a pair of pegs 4 and 5, which are received in alining sockets 6 and 7 of the handle 2, when the handles 1 and 2 are in closed position. The handle 2 is moved to an open position as illustrated in Fig. 2 or Fig. 3 and a razor blade 8 having openings therein is received upon the handle 1 and the pegs 4 and 5 pass therethrough. The peg 4 is inclined in the direction of the peg 5 to cause a slight reduced space between the upper end of the pegs 4 and 5 to firmly hold the razor blade 8 upon the pegs. The razor blade 8 is first positioned on the peg 5 and the operator then bears downwardly with the thumb and forefinger upon the center of the blade 8 which will cause it to bend intermediate its length and pass over the end of the inclined peg 4. After the blade 8 has passed over the end of the peg 4 it will spring back to its normal position and firmly clamp itself upon the pegs 4 and 5. The operator may then carry the handles around in an open position if desired without the danger of the razor blade 8 slipping or falling from the pegs 4 and 5.

The handles 2 and 3 are provided with strop engaging faces 9 and 10 with inclined edges 11 and 12, providing means for supporting the razor blade 8 in an inclined or sharpening position upon a strop so as to provide a proper incline to the blade 8, when the operator draws the device over the strop to sharpen the edges of the razor blade.

In operation the razor blade 8 is placed upon the pegs 4 and 5 and the handle 2 is closed downwardly upon the handle 1 firmly holding said blade 8 between the handles 2 and 3 against any movement. The operator then draws the handles 1 and 2 downwardly over a strop in closed position which will support the blade 8 in an inclined or sharpening position and on the upward stroke of the strop, the handles are rolled on one of the strop engaging faces until the blade 8 assumes a reverse incline or sharpening position to sharpen the opposite edge of the razor blade 8.

Having thus described my invention, what I claim is:

A razor blade holder comprising a pair of handles, a hinge secured to one end of each of said handles, one of said handles pro-

vided with a pair of sockets and one of said sockets inclined in the direction of the other socket, and a pair of pegs secured to the other handle and received by the sockets to support a razor blade between the handles, one of the pegs is inclined in the direction of the other peg to coöperate with the inclined sockets to hold the razor blade firmly

upon the pegs when the handles are in an opened and closed position. 10

In testimony whereof I affix my signature in presence of two witnesses.

MAX APSTEIN.
